(57) **CLAIM**

The ornamental design for an internal padding assembly of a protective sports helmet as shown and described.

DESCRIPTION

FIG. 1 is a front perspective view of a first embodiment of an internal padding assembly of a protective sports helmet showing our new design.

FIG. 2 is a rear perspective view of the internal padding assembly of the protective sports helmet of FIG. 1.

FIG. 3 is a bottom perspective view of the internal padding assembly of the protective sports helmet of FIG. 1.

FIG. 4 is a front view of the internal padding assembly of the protective sports helmet of FIG. 1.

FIG. 5 is a rear view of the internal padding assembly of the protective sports helmet of FIG. 1.

FIG. 6 is a left side view of the internal padding assembly of the protective sports helmet of FIG. 1.

FIG. 7 is a right side view of the internal padding assembly of the protective sports helmet of FIG. 1.

FIG. 8 is a top view of the internal padding assembly of the protective sports helmet of FIG. 1.

FIG. 9 is a bottom view of the internal padding assembly of the protective sports helmet of FIG. 1.

FIG. 10 is a front perspective view of a second embodiment of an internal padding assembly of a protective sports helmet showing our new design.

FIG. 11 is a rear perspective view of the internal padding assembly of the protective sports helmet of FIG. 10.

FIG. 12 is a bottom perspective view of the internal padding assembly of the protective sports helmet of FIG. 10.

FIG. 13 is a front view of the internal padding assembly of the protective sports helmet of FIG. 10.

FIG. 14 is a rear view of the internal padding assembly of the protective sports helmet of FIG. 10.

FIG. 15 is a left side view of the internal padding assembly of the protective sports helmet of FIG. 10.

FIG. 16 is a right side view of the internal padding assembly of the protective sports helmet of FIG. 10.

FIG. 17 is a top view of the internal padding assembly of the protective sports helmet of FIG. 10; and,

FIG. 18 is a bottom view of the internal padding assembly of the protective sports helmet of FIG. 10.

The unevenly broken lines (i.e., dash-dot-dot-dash lines) depicting a helmet shell represent environmental subject matter that forms no part of the claimed design. The evenly broken lines (i.e., dash-dash lines) depict portions of the
